UNITED STATES PATENT OFFICE.

PARKER C. MARSH, OF TROY, NEW YORK.

FEATHERING PADDLE-WHEEL.

SPECIFICATION forming part of Letters Patent No. 310,451, dated January 6, 1885.

Application filed April 26, 1884. (No model.)

To all whom it may concern:

Be it known that I, PARKER C. MARSH, a citizen of the United States of America, residing at Troy, in the county of Rensselaer 5 and State of New York, have invented certain new and useful Improvements in Propeller-Wheels; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to certain new and useful improvements in feathering paddle-wheels, the object of my invention being to provide a wheel which may be rotated in either direction, and which will present the 20 paddles to the water in a vertical position; and to this end my invention consists in the construction and combination of parts, as will be hereinafter set forth.

In the accompanying drawings, Figure 1 is 25 a vertical section. Fig. 2 is a sectional view taken through the line $x-x$ of Fig. 1, and Fig. 3 is a detail side view.

A represents the side of the vessel, which is 30 provided with bearings, through which the driving-shaft A' passes, upon which driving-shaft is rigidly attached the paddle-wheel B.

Upon a central hub, B', are rigidly secured the spokes and rim of the paddle-wheel, the inner spokes being provided with radial slots 35 b, within which operate suitable slides, which are connected to the paddles. The paddles C are concaved in cross-section, and are provided on their rear portions with projecting arms e, having at their ends projecting portions, which pass through perforations in the 40 rims of the wheel opposite the radial arms thereof.

Rigidly attached to the inner side of the 45 paddles are short arms d, the end d' of these arms being of sufficient length to extend beyond the periphery of the inner end of the wheel, while the longer or opposite end, d'', of these arms is pivotally connected to a connecting-arm, e, which is attached to a sliding block, E, which is secured within the slot b in the radial arms.

Attached to the lower end of the arm e, at a point opposite the sliding block E, are anti-friction rollers F, which operate within suitable guides for actuating the paddles.

55

Attached to the side of the vessel so as to project over the inner rim of the paddle-wheel at a point above its center are projecting arms G, which are adapted to engage with the projecting ends d' of the arm d and throw the 60 same off its center when the wheel is in operation.

Secured to the side of the vessel or framework A are suitable guide-plates, H I I' J, which are arranged as shown, so as to provide eccentric passages K K' L L' about the shaft-opening a, which passes through the upper part of the plate H.

Between and around the plates H I I' J is a depressed passage-way for the reception of 70 the anti-friction rollers F, which are attached to the end of the arms e.

Journaled upon the upper and lower ends of the plates I I' are weighted dogs M, which assume normally the position shown in Fig. 3, 75 the weights of these dogs operating within suitable recesses formed in the frame A, while the outer portions operate on a line with the plates H I I' J.

The operation of my invention will be fully 80 understood by following the positions assumed by the anti-friction rollers F in the guideways, and the positions assumed by the paddle, which is operated thereby. The paddle l, when in the water, at the lowest portion 85 of the wheel will be in a vertical position, the arm e being inclined from the radial slotted spokes, and the anti-friction roller will be located immediately under the ends of the weighted dogs M, and as the wheels are ro-

9c

tated this anti-friction roller will travel in a passage, K', between the guide-plates I' J, when it will gradually be turned over, a complete rotation of the same being accomplished when it reaches a point opposite the tripping-arm G, which will throw the arms d e off a dead-center, so as to prevent binding of the parts. When the anti-friction roller reaches a point opposite the shaft or center of the plate H, it will be guided by the weighted dog attached to the upper portion of the plate I into the way L, and the anti-friction roller travel- 95 100

ing in this way will turn the paddle so that it will enter the water in a nearly vertical position, the anti-friction roller F passing out of the guide L into the passage K. When the paddle-wheel is reversed, the anti-friction roller will travel in the guide-passages K L', and will operate in a manner similar to that hereinbefore described. The dogs M, as shown, have spur-extensions m, which are normally maintained by the weighted portion of said dogs in the positions illustrated in Fig. 3—that is to say, the spurs of the upper dogs are so located as to close or partly close the upper end of the passages K K', while the spurs 15 of the lower dogs are thrown with their free ends against the bottom of the plate H, thus closing the lower ends of the inner passages, L L'. By this means the roller traveling upward in the passage K' will act as a wedge on 20 the spur-extension at the top and move the same sufficiently to permit said roller to pass from passage K', but contacting with the concave side of the spur closing the passage K the said roller will be deflected into the inner passage, L, and will afterward move the spur, closing the lower end of said passage to again 25 enter the passage K'.

It will be readily seen from the foregoing that the paddles, as they enter the water, will 30 not have a tendency to lift the vessel, and will leave the water freely without an expenditure of power; also that there will be less waves caused than by paddle-wheels of ordinary construction.

35 I claim—

1. The combination, in a propeller-wheel, of a drive-shaft suitably journaled, a wheel provided with parallel rim-sections, and having its spokes slotted as described, a series of 40 paddles having journals bearing in said rim-sections, an arm, d, connected to one of said journals of each paddle, an arm, e, connected

to arm d and to a block located in one of the spoke-slots, devices for moving said block in said slot, and a trip device, G, for contacting 45 with the end of the arm d when the same is in line with the arm e, substantially as set forth.

2. The combination, in a propeller-wheel, of a drive-shaft suitably journaled, a wheel 50 provided with parallel rim-sections, and having its spokes slotted as described, a series of paddles having journals bearing in said rim-sections, a block located in the slot of each of the spokes and connected to one of the journals 55 of each of the paddles, a roller carried by said block and adapted to travel in eccentric guide-passages formed in the adjacent side of the vessel, and weighted dogs having spurs m closing the upper ends of one set of passages 60 and the lower ends of another set, substantially as set forth.

3. In a feathering paddle-wheel, the pivoted paddle-blades C, formed of a single piece of metal, and hollowed so as to be concave 65 both longitudinally and laterally, and provided on the rear with raised portions e, from which project the side journals, substantially as shown.

4. In a self-feathering paddle-wheel, the 70 guide-recesses K K' L L', provided with weighted dogs M, pivoted as shown, and an anti-friction roller adapted to travel therein, and connected to the paddles so that they will operate so as to present their concave surface to the water when the wheel is rotated in either direction, substantially as shown.

In testimony whereof I affix my signature in presence of two witnesses.

PARKER C. MARSH.
